UNITED STATES PATENT OFFICE.

OTTO HANSER, OF ROCKVILLE, CONNECTICUT.

DRIVING-GEAR FOR BICYCLES.

SPECIFICATION forming part of Letters Patent No. 367,293, dated July 26, 1887.

Application filed March 30, 1887. Serial No. 233,095. (No model.)

To all whom it may concern.

Be it known that I, OTTO HANSER, a citizen of the United States, residing at Rockville, in the county of Tolland and State of Connecticut, have invented a new and useful Gear to be Used in Bicycles, of which the following is a specification.

The object of my invention is, first, to increase the speed of any bicycle two, three, or more times through the means of gear-wheels; second, to provide the necessary ratchet-box to apply the speeded motion of the gear to the propelling-wheel or the bicycle-wheel proper; third, to provide the necessary hub of the propelling-wheel; fourth, to afford the necessary bearings for properly steadyng the propelling-wheel on the axle. I attain these objects by mechanism illustrated in the accompanying drawings, in which—

Figure 1 is the entire view of the improvement on and in a bicycle-wheel, one half being the horizontal section and the other half being the top view of it. Fig. 2 shows the vertical section of an axle as improved at the line of the cross-shaft *d*. Fig. 3 shows the ratchet-box and the notched ring as detached from the hub or flange. Fig. 4 is a side view of the bearings, with the ring and its cavities holding rollers.

The axle consists of three shafts. One, the innermost, is a solid rod, *a*, passing through the entire length of the axle, nutted on both sides, keeping frame, wheel, and everything nicely in place. The second shaft, *b*, is a strong tube covering the rod *a*. It reaches from outside the propelling-wheel to the center of it. It transfers the driving-power to a central disk which has a toothed bevel on each of its sides. There are two tubes, one on each side, secured to this central disk at a vertical angle by means of metal plates screwed on the tubes and then fastened to the wheel or disk. The third shaft, *c*, is to be a still shaft, covering the driving-tube, one on each side of the disk, which it does not touch. Its inner ends have shoulders or supporters and suitable bearings, through which the cross-shaft *d* from small wheel 2 passes, and is thus held in its proper position. Passing through the flange *F* outward this shaft *c* is firmly secured to a piece of metal, *c'*, and this again is secured to the ordinary frame. Thus this third tube becomes

a horizontal part of the frame, projecting through the hub or flange *F*, and since itself is immovable it will prevent the smaller wheels 2 and 3 and their shafts *d* from moving, so that they cannot slip around with the disk when in motion.

Gear-wheel 1 or disk is in the center of the propelling-wheel, tight to the tube *b*. We might call it the "driving-wheel," set in rotation by the power of driver outside the propelling-wheel and transmitted by the driving-tube *b*. This wheel 1 is bevel-geared on both sides. On each side there is a wheel, 2, of small diameter, also bevel-geared correspondingly to the larger wheel, with which it engages; but it turns so many more times as its diameter is smaller than that of the larger disk 1. Its speeded motion is carried across the axle by a rod or shaft, *d*, to which it is keyed. This rod *d* rests upon and is kept in position by suitable bearings, *c''*, on the supporter *c'* of the tube *c*. This shaft *d* transmits the speeded motion of wheel 2 across the axle to another set of miter-wheels, one of which, 3, is keyed on this rod *d*. The other wheel, 4, of the same diameter, rides on the tube *c*. The wheel 4 is called a "wheel" only because of its bevel-gear corresponding to that of wheel 3. In fact, this gear 4 is secured to a ratchet-box, 9'. Thus the same speeded motion of wheel 2 is by bevel-gearing imparted to this ratchet-box, which again turns the propelling-wheel proper at its own rate. This ratchet-box 9' inside of the wheel (one for each side) is of course without a spring-chamber; but where on its outer side wall the bevel-gear 4 is secured it has on its inside the pawl-ring 7, or rather only strong projections or tangs, in which the pawls 10 are hinged, which spread into the notched ring 8', extending from the wheel over these pawls. The friction piece or band 7 rides and rubs on the tube *c*, but directly forward of the pawls 10, to which it is connected by means of a link, 9, hinged both in the friction-piece and pawls. The pawls 10 turn the notched ring 8' the same moment when the bevel-gear outside is set in rotation, and at the same rate.

The hub consists of the two flanges *F*, one on each side of propelling-wheel, each greatly thickening toward its center and bearing on tube *c*.

The bearings, Fig. 4, are of peculiar construction. They are designed to serve two purposes—first, to reduce the friction of the flange or hub F on the axle to a minimum. Roller-bearings are best adapted therefor. The rollers consist of two cylinders or heads, *r*, held together by a strong pin, *n*, itself freely turning in the cylinders. To prevent the rollers from rolling together, the pins are laid in a ring or collar, *m*, the periphery of which is cut out at intervals nearly as deep as the pins *n* are thick. This collar turns around the axle *c* without touching it, while the small cylinders or heads *r* roll easily between the thick flange and axle. The other purpose of these rollers is to steady each side of the wheel. If the rim receives a blow or shock, the wheel is likely to bulge out at its center. Ordinarily the hub connecting both sides prevents that; but in this case the rollers must prevent the outward bulging. Therefore the hub or flange F is cut on its broad riding-face exactly to fit the form of the rollers, the middle of the riding-surface extending down so as to almost touch the neck or pins *n* of the rollers *r*, and the two sides *p* and *p'* to rest and roll on the roller-heads *r*. It is best to make the flange at its center of three plates firmly screwed to one another—the thickest one where the greatest strain is. The outermost plate, *p*, and innermost plate, *p'*, ride on the roller-heads *r*, while the middle plate, *o*, extending farther, almost touches the neck of the rollers. Thus the bulging of the wheel is prevented, because the middle plate, *o*, is held fast and steady between the two roller-heads *r*, the roller *s* also being prevented from moving outward by butting against the metal plate *c* from tube *c*, secured to the frame.

I am aware that ratchet-boxes are used to propel a bicycle in which pawls are operated by a friction-piece; also, that roller-bearings are applied to bicycles. I do not claim, therefore, such contrivances, broadly; but

What I claim as my invention, and desire to secure by Letters Patent, is—

1. In the propelling-wheel of a bicycle, the combination of tubes covering the axle or rod *a*, and transmitting the power to a central rotary disk having a toothed bevel on each of its sides, as described.

2. In the propelling-wheel of a bicycle, the

combination of a central rotary bevel-gear wheel with a wheel on each side of said central wheel, but of smaller diameter than that of said central wheel, also having a bevel-gear corresponding to that of said central wheel, by which it is set in rotation, but revolving so much quicker as it is smaller than the central wheel, all as shown, and for the purpose specified.

3. In the propelling-wheel of a bicycle, the combination of rods serving as axles to the wheels 2, to which they are keyed at one end and crossing the fixed tubes *c*, having their bearings on the shoulders of said fixed tubes *c*, with other bevel-gear wheels 3, respectively keyed on the other end of rod *d*, communicating the rotation of wheels 2 to wheels 3, substantially as shown.

4. The combination of a bevel-gear, 4, corresponding to and set in rotation by the bevel-gear of wheel 3, with a ratchet-box, 9', to which it is secured, substantially as set forth.

5. A propelling-wheel for a bicycle, having the ratchet-boxes and driving mechanism, in which the pawls are hinged in strong tangs 7, extending from rear wall about or little more than midway between that shaft and the notch-ring, thus leaving the shaft entirely free (excepting a space for the friction-band) for the central part of hub deeply to enter into the ratchet-box, all substantially as set forth.

6. A bicycle-wheel comprising two flanges, each flange being provided with a notch-ring 85 on its inside to engage driving-pawls and thickened toward its center or bearing-face, and shaped upon its bearing-face to fit the rollers *r*, in combination with said rollers *r*, and a collar fitting over the pins of the rollers, upon which the heads of the rollers turn freely, as set forth.

7. The combination, in a bicycle, of the following elements, namely: two tubes, each covering a tube, *b*, and supporting a cross-shaft, *d*, and a ratchet-box and bearing of a flange, *F*, and a metal plate secured upon the end of the tube and to the frame of the machine, all substantially as described.
